SYSTEM FOR ADJUSTING THE FUEL SUPPLY
IN INTERNAL-COMBUSTION ENGINES

Eugen Stump, Stuttgart-Unterturkheim, Germany, assignor to Daimler-Benz Aktiengesellschaft, Stuttgart-Unterturkheim, Germany

Application September 16, 1949, Serial No. 116,062
In Germany October 1, 1948

14 Claims. (Cl. 123—98)

1

This invention relates to a device for the adjustment of the quantity of fuel supplied to internal combustion engines and more particularly to internal combustion engines of the injection type for motor vehicles.

It is known to stop the engine with the aid of a rotary handle or rotary knob, which serves simultaneously for the variable adjustment of a no-load limit position for the foot-operated fuel governing gear, by turning the rotary handle or rotary knob beyond the no-load position up to the complete cutting off of the fuel supply or to the stoppage of the engine. This method of stopping the machine has the drawback, however, that in order to re-start the engine the no-load position has to be readjusted again and again which requires an additional manipulation and attention and reduces the reliability and accuracy of the adjustment. Moreover, it is relatively troublesome to turn the rotary knob up to the stoppage of the engine.

It is the object of the present invention to avoid these disadvantages.

A special object of the present invention is to ensure a permanent readiness of the engine for operation with accurately adjusted idling even after the stoppage of the engine and moreover to render possible the stopping itself in a very simple and quick manner.

With these objects in view, an important feature of the present invention consists in the provision of a device which permits adjustment of the engine to a predetermined limit load, more particularly to a predetermined quantity of fuel for idling, and moreover, to stop the engine independently of this adjustment, more particularly by cutting off the fuel supply. Preferably, for stopping the engine, the device is provided to be operated in such a way that on termination of the operating impulses intended to stop the engine the device will automatically return to its limiting position which has been adjusted independently thereof. To this end the device comprises a bearing member which carries the operating gear and with relation to which the gear can be adjusted for changing the no-load setting, said bearing member not being affected by said adjustment but being adjustable as a unit together with the operating gear, for stopping the engine. The variable adjustment of the idling in this case is effected advantageously by screwing a rotary knob which can be threadably engaged with the bearing or carrying member and connected with the lever gear so as to be non-shiftable in an axial direction, while for stopping the machine the rotary knob together

2

with the carrying member is adjustable in an axial direction, advantageously against spring action. Both these movements can be carried out independently of each other so that the once adjusted no-load position of the device or with it (provided the other conditions remain unchanged) the once adjusted no-load speed of the engine remain unchanged, no matter how many times the device has been operated in the meantime for stopping the engine. Moreover, the push button-like operation of the device permits a particularly advantageous simplification and acceleration of the stopping operation.

In normal working order it will be sufficient in general to actuate the device for a few moments only (e. g., by depressing the knob), in order to stop the engine, while letting it go after the stopping of the engine, so that it may hereafter return automatically and immediately to its running light or idling position. However, under certain conditions, e. g. in case of a downhill journey of the vehicle, it may be desirable to leave the engine in its stopped position for a longer period without having to actuate the device permanently by hand (or the like). According to a further feature of the invention, therefore, there is provided a locking device by means of which the operating device can be retained in its position for stopping the engine. This may be achieved, e. g., in a simple manner by locking the carrying member serving for the stopping, after shifting it into its stopping position, at a fixed wall member or the like, by slight lateral swinging, against return to its running light position, e. g. by means of an annular notched surface. Advantageously a lever provided with a stop and permitting the part of the governing gear connected with the quantity governing member to move back to the adjustable limit position defined by the device, serves to transmit the action of the device upon the fuel governing rod and lever gear, while the part of the rod and lever gear connected with the operating lever ("gas pedal") may remain unhindered in its motion.

Other and further objects, features and advantages of the invention will be pointed out hereinafter and appear in the appended claims forming part of the application.

In the accompanying drawing a new preferred embodiment of the invention is shown by way of illustration and not by way of limitation.

In the drawing:

Fig. 1 is a general survey, in a simplified representation, showing the device with the governing gear mounted at a vehicle diesel engine,

Fig. 2 is a section through the device on a larger scale, and

Figure 3 is a view similar to that of Figure 2 with the parts in a different relative position.

The quantity of fuel supplied to the vehicle driving engine through the injection pump 1 is governed by a lever 2 which serves to adjust, e. g. a toothed governing rack mounted within the pump for turning the pump pistons or to effect the regulation in any other suitable manner (e. g. by adjusting the stroke of the pump piston). The lever 2 is connected, through a rod 3, with a lever 4 mounted on the shaft or pin 5. A return spring 6 which in the practical embodiment is advantageously arranged between the rod 3 and the shaft 5, tends to retract the lever 2 with the rod and lever gear system 3, 4, from the full load position V into the running light position L which is defined by a stop 7 against which the lever 4 bears and which is arranged at one end of a two-armed lever 8 also mounted on the shaft 5. The other end of this lever is connected to a Bowden cable 9 which in the manner hereinafter described can be operated by a device 11 with operating knob 12 secured to the dash board 10, thereby adjusting also the stop 7.

Mounted for rotation on the shaft 5 is moreover a further lever 13 including a stop 14 and coupled, e. g. adjustably, with a rod 15 whose opposite end is connected to the foot lever 18 (gas pedal) which is pivoted at 16 and urged upwards by a spring 17 for arbitrary adjustment of the amount of fuel. It will be understood that the spring 17 may also be arranged in the pivot 16 or at any other point and designed in any suitable manner.

Fig. 2 shows the device 11 on a larger scale. The casing of the device consists of a cap member 19 of pressed sheet metal and a bearing member 20 which is centered in an opening of the dash board 10. Both parts are interconnected, e. g., at the flanges 21 and commonly held in an axial direction by a cap nut 22 screwed on to the bearing member 20. Welded to the casing 19 is a U-shaped member 23 carrying the casing 24 for the Bowden cable. The casing 19 moreover possesses a non-circular, e. g. square hole 25 in which is slidably but non-rotatably guided, advantageously with a small play, a carrying member 26 which at its opposite end is mounted in the bearing member 20 in such a way that it is free to move with respect thereto in a left hand direction, but prevented from moving to the right by a spring ring 27. A spring 28 inserted between this spring ring and the left hand wall of the cap member 19 forces the carrying member in a right hand direction into engagement of the spring ring 27 with the bearing member 20. The carrying member has an annular notch or turned off portion 29 serving as a locking notch in a way which will be hereinafter described.

The operating knob (rotary knob) 12 is moreover coupled, so as to be rotatable but relatively non-slidable on the one hand, by means of a thread 30, with the carrying member 26 and on the other hand, by means of a spring ring 31 or the like, with the cylindrical part 32 of a slide 33 which is of square shape and axially slidable in a square hole disposed in a collar 34 of the carrying member 26, the end 9' of the Bowden cable being secured to the slide 33.

The device according to the invention operates as follows:

In the drawing the device is shown in the running light position corresponding to the position

L of the lever 2. The lever 4 bears against the stop 7 while a play "e" is existing between the lever 4 and the stop 14. Therefore, when depressing the pedal 18, the lever 2 can play only between V and L. By turning the knob 12, the slide 33 and with it the Bowden cable 9 can be axially moved, whereby the lever 8 or the stop 7 is adjusted to the one or the other side and accordingly the no-load limit position L is more or less changed. The carrying member 26 remains immovable in its position. Now, if it is intended to stop the engine, the knob 12 is pressed to the left in an axial direction, whereby the knob 12, the carrying member 26 and the slide 33 are moved as a unit against action of the spring 28 and the lever 8 is swung in the direction x by such an amount that the lever 2 under action of the spring 6 which causes the lever 4 to follow the stop 7, moves to the zero position 0, thus stopping the engine. In order to keep the device in the stopped position it is sufficient to exert a light pressure, transversely to the axial direction, upon the knob 12, after the same, or the carrying member 26, has been moved into the extreme left hand position; the locking notch 29 thereby engages behind the left hand front face of the bearing member 20 (whereby the carrying member 26 swings slightly about the interior edge of the opening 25) and thus locks the device under the pressure of the spring 28. By a slight oppositely directed transverse pressure the notch 29 is again disengaged from its position behind the wall of the bearing member 20 so that the spring 28 causes the device to bound back into the originally adjusted running light position, as shown in the drawing. If, in the normal case, there has been no previous locking by the notch 29, the device will automatically return to the adjusted running light position as the pressure exerted on knob 12 decreases.

It will be understood that the invention is not restricted to the embodiment as illustrated. Instead of locking the parts by the notch 29 it is also possible to provide movable automatic locking members or e. g. members which are to be operated separately. By way of alternative, rod and lever systems may be provided instead of the Bowden cable for operating the device. Moreover, the stop 7 for adjustment of the no-load position may be arranged in any other manner, e. g., as a transversely slidable stop or the like. Furthermore, a similar governing system or method may be provided, e. g., for carburetor engines or the like.

What I claim is:

1. A system for controlling and interrupting the operation of an internal combustion engine comprising control means for controlling the supply of fuel to the engine, means influencing said control means for selectively adjusting the supply of fuel in correspondence with the desired operating conditions of the engine, a device influencing the control means for adjusting the supply of fuel at a minimum value and a device also influencing the control means for temporarily interrupting the supply of fuel, both said devices being so interconnected that the first device can be made inoperative or operative by the second device without change in the adjustment thereof.

2. A system for controlling and interrupting the operation of an internal combustion engine comprising control means for controlling the supply of fuel to the engine, means influencing said control means for selectively adjusting the supply of fuel in correspondence with the desired work-

ing conditions of the engine, a device influencing the control means for adjusting the supply of fluid to no-load conditions and a second device also influencing the control means for temporarily interrupting the supply of fuel, both said devices being so interconnected that the first said device may be actuated by the second said device from an operative position to an inoperative position and back to an operative position without altering the adjustment.

3. A system as in claim 2 further comprising a common actuating member and a common actuating link for both said devices.

4. A system for controlling an internal combustion engine comprising control means for adjusting the fuel supply, further means influencing said control means for selectively adjusting the fuel supply in correspondence with the desired working conditions of the engine, additional means influencing said control means and comprising an adjustable carrying member, an actuating member supported by the adjustable carrying member and including means for adjustably positioning the actuating member relatively to the carrying member, and transmission means connecting the actuating member to the control means for transmitting to the control means selectively either the relative movement of the actuating member alone or the movement of the carrying member and of the actuating member.

5. A system according to claim 4 wherein the means for selectively adjusting the fuel supply and the additional means each further comprise an abutment member engageable with clearance with the control means.

6. A system for controlling an internal combustion engine comprising control means for controlling the fuel supply to the engine, means influencing said control means for selectively adjusting the fuel supply, an abutment member engageable with the control means to limit downward selective adjustment of the fuel supply, a connecting rod for adjusting the position of the abutment member, an actuating member for the connecting rod, a movable carrying member supporting the actuating member whereby the actuating member is movable either relatively to or with the carrying member in such a manner that relative movement of the actuating member will transmit movement to the abutment member within an idling range of the engine and that the joint movement of the carrying member and actuating member will displace the abutment member to interrupt the fuel supply.

7. A system according to claim 6 wherein the actuating member is threadably engaged in the carrying member and the carrying member and actuating member are movable together along a common axis.

8. A system according to claim 6 wherein the actuating member is threadably engaged in the carrying member and wherein the carrying member and actuating member are movable together along a common axis, in combination with spring means urging the actuating member relatively to the carrying member into a position corresponding to no-load operation.

9. A system according to claim 6 wherein said connecting rod comprises a transmission member rotatable with the actuating member, said transmission member being axially fixed relatively to said actuating member, the combination further comprising a relatively fixed part whereby the carrying member is held against rotation and free for axial movement in said fixed part, spring

means being interposed between said carrying member and fixed part.

10. A system according to claim 6 wherein the actuating member comprises an actuating button.

5 11. A system for controlling and interrupting the operation of an internal combustion engine comprising a fuel adjustment device, a relatively fixed housing member, a carrying member located in and movable relatively to the housing

10 member, the carrying member being spring urged into an end position and slideable against the spring action, an actuating member adjustably positioned by threaded engagement in the carrying member, an element coupled with the actuating member, an abutment member connected with said element, said abutment member being so engageable with said fuel adjustment device that screw adjustment of the actuating member will adjust said actuating member relatively to

15 the carrying member thereby setting the fuel adjustment device to a predetermined minimum supply and that sliding of the carrying member against spring action will adjust said carrying member together with said actuating member and

20 element as a unit thereby enabling interruption of the fuel supply.

12. A system according to claim 11 comprising means for locking the carrying member in an adjusted position against such spring action.

25 13. A system according to claim 11 wherein the carrying member is laterally displaceable in combination with complementarily engageable parts on an edge of the carrying member and on the housing member whereby the carrying member

30 may be locked in adjusted position against said spring action by engagement of said parts.

14. A system for controlling and interrupting the operation of an internal combustion engine comprising a control rod for controlling the fuel supply, an element for actuating the control rod, a clearance being provided between the element and the control rod, an abutment member for limiting the movement of the control rod within the said clearance and a device for adjusting the position of the abutment member comprising a relatively fixed part, an actuating member engageable with the abutment member and an adjustable carrying member for said actuating member, means for displacing the actuating member relatively to the carrying member, abutment means for the carrying member on the relatively fixed part, spring means urging the carrying member against said abutment means and against which the carrying member and actuating member may be manually displaced toward the relatively fixed part, in such manner that, upon release of said actuating member, said spring means will return said actuating and carrying members and said abutment member to

35 40 45 50 55 60 original adjusted position.
